(57) **CLAIM**

The ornamental design for a folding box, as shown and described.

DESCRIPTION

1. Folding box

1.1 : Perspective

1.2: Front

1.3 : Back

1.4: Left

1.5 : Right

1.6: Top

1.7 : Bottom

Reproductions 1.1 to 1.7 are views of the folding box in a condition that the claimed design has been completely folded, with a binding ring closed.

1.8 : Perspective

1.9 : Front

1.10 : Back

1.11 : Left

1.12 : Right

1.13: Top

1.14: Bottom

Reproductions 1.8 to 1.14 are views of the folding box in a condition that the claimed design has been completely unfolded with a binding ring closed.

1.15 : Perspective

1.16 : Front

1.17 : Back

1.18 : Left

1.19 : Right

1.20: Top

1.21 : Bottom

Reproductions 1.15 to 1.21 are views of the folding box in a condition that the claimed design has been completely folded with a binding ring opened.

1.22 : Perspective

1.23 : Front

1.24 : Back

1.25 : Left

(Continued)

1.26 : Right

1.27: Top

1.28 : Bottom

Reproductions 1.22 to 1.28 are views of the folding box in a condition that the claimed design has been completely unfolded with a binding ring opened.
